Dec. 744

Conrad Harris & Paul M. Goines, of Cincinnati, O.

Letter Patent No. 747 - dated December 11, 1855.

~~~~~

The schedule referred to in these Letters Patent and making part of the same.

~~~~~

To all whom it may concern,

Be it known, That we, Conrad Harris & Paul M. Goines, both of the city of Cincinnati, county of Hamilton, State of Ohio, have invented or produced a new and original design for Coal Parlor Stoves, and we do hereby declare the following to be a full and exact description of the same, reference being had to the annexed drawings and to the letters of reference marked thereon - to wit, letter A, being a front view of the stove.

That we claim therein as new and desire to secure by Letters Patent is the design configuration and arrangement of the several ornaments as set forth in the annexed drawings forming a new and original design for a Coal Parlor Stove, to be known and called the Baron.
